UNITED STATES PATENT OFFICE

EDWARD B. PATTERSON, OF MERCHANTVILLE, NEW JERSEY, ASSIGNOR TO RADIO CORPORATION OF AMERICA, A CORPORATION OF DELAWARE

DESIGN FOR AN ACOUSTIC PANEL FOR VEHICLES

Application filed January 30, 1932. Serial No. 42,678. Term of patent 7 years.

To all whom it may concern:

Be it known that I, EDWARD B. PATTERSON, a citizen of the United States, and a resident of Merchantville, in the county of Camden and State of New Jersey, have invented a new, original, and ornamental Design for an Acoustic Panel for Vehicles, of which the following is a specification, reference being had to the accompanying drawing, forming a part thereof.

Figure 1 is a side view of a relatively thin acoustic body-panel for vehicles showing my new design, with the panel closed; and

Fig. 2 is a similar view thereof with the panel opened and with a plurality of loud speaker grilles disclosed.

I claim:

The ornamental design for an acoustic panel for vehicles, as shown and described.

EDWARD B. PATTERSON.
